UNITED STATES PATENT OFFICE.

HENRY A. DOTY, OF JANEVILLE, WISCONSIN.

IMPROVEMENT IN WOOD-SCREWS.

Specification forming part of Letters Patent No. **173,115**, dated February 8, 1876; application filed June 6, 1873.

To all whom it may concern:

Be it known that I, HENRY A. DOTY, of Janesville, Rock county, State of Wisconsin, have invented Improvements in Wood-Screws, of which the following is a specification:

The object of this invention is a wood-screw constructed, as fully described hereafter, to render any preliminary piercing of the wood unnecessary, and to insure the travel of the screw in the direction in which it is started; and this object I effect by constructing the screw with a projection extending beyond the thread, as shown in the accompanying drawing, the three figures of which illustrate the screw and the different ways in which it may be driven into the wood.

Instead of ending the screw A at the point B, where the thread terminates, the core C is continued sufficiently long to form a tapering sharp-pointed projection, D, which may be forced into the wood easily, and answers as a support for the screw until the latter is driven farther by turning the same with a screw-driver.

Gimlet-pointed screws will readily drive themselves into the wood after they are started, provided there is no cross-grain or knots in the way; but it is a hard matter to start them in the direction desired without first

making a hole to receive them, and after they are fairly entered, the screw, in consequence of the shape of the gimlet-point, will follow the grain of the wood, and turn aside from a straight course on coming in contact with cross-grain or knots.

My invention provides a remedy for the above defect, as the center point, being sharp, pierces the wood easily, no matter what is the resistance of cross-grain or knots, and necessarily advances without a deviation from a straight line, thereby preventing the breaking of the screw, which would be the case if the screw had to turn aside for every obstruction it met. Again, the sharp point answers the purpose of an awl to exactly locate the starting place of the screw on any surface.

I claim—

A wood-screw provided with a pointed projection, D, extending beyond the thread, as set forth.

In testimony that I claim the foregoing I have hereunto set my hand this 28th day of May, 1873.

HENRY A. DOTY.
